OUTBOARD MOTOR HANDLE

Tolbert Frank Hobson, St. Petersburg, Fla.

Application August 11, 1936, Serial No. 95,445

7 Claims. (Cl. 74—543)

This invention relates to an outboard motor and more particularly to a steering handle therefor.

As is well known the propeller of an outboard motor is secured to a propeller shaft by means of a shear pin which must be replaced in the event of damage. In order to replace the shear pin an extra shear pin must be available as well as suitable tools for performing the replacing operation.

Outboard motors are continually being changed from one craft to another or removed for storage and accordingly shear pins, cotter pins and tools are frequently lost or if kept in a separate kit, the latter is forgotten or left behind.

The extremely annoying situation of being out on the water away from home, cottage or camp when it becomes necessary to replace a shear pin and the spare shear pin and tools are not available results in the unpleasant experience of a long and tiresome pull on the oars in the hot sun, and of being subjected to the elements such as a drenching from an oncoming storm or other unpleasant or annoying circumstances.

It is an object of the invention to overcome the problem just described by providing a steering handle having a hollow kit containing portion not only for containing extra shear pins and necessary wrenches or tools for replacement of the same but at the same time to provide a reinforcement for the handle.

It is a further object to provide a handy implement for removing and installing the shear pins and of a size to be readily retained within the hollow portion.

Other objects and advantages will be apparent from the following description taken in connection with the accompanying drawing which is made a part hereof, and wherein

Fig. 1 is a perspective of an outboard motor with a handle illustrating one application of the invention;

Fig. 2, an enlarged fragmentary detail of the handle with parts broken away to disclose the interior;

Fig. 3, a similar view of a modified handle section; and

Fig. 4, a perspective of the sections of the handle prior to assembling.

Referring to the drawing an outboard motor 10 is mounted upon a supporting bracket 11 for pivotal movement by means of a hollow handle consisting of two parts, one of which is provided with a hand grip 12, and the other 13 of which has a flanged bearing element 14 which is fas-

tened to the motor for swinging the motor about its vertical pivot.

The handle is detachable and is of the swing up type or is in other words swingable from a depending to a substantially horizontal position.

The hand grip section 12 of the handle is provided with an internally threaded thimble or collar 15 for engagement with cooperative screw threads 16 on the hollow handle section 13. As shown particularly in Fig. 3 this hollow handle section 12 is provided with a reduced hollow extension 17 which serves the three fold purpose of supporting the internally threaded collar 15, as a reinforcement for the joint when the pipe sections are assembled, and as a receptacle for spare shear pins and cotter pins as well as a receptacle for a wrench or other satisfactory tool for applying and removing the same. The pipe or tube 17 has one end closed and has its free end provided with a closure plug or member 18 which seals the compartment within the tube.

It will be readily apparent from the above description that a handle is provided which has the appearance of the conventional handle, is of improved stronger construction, and at the same time has a sealed tool compartment.

A handle of the above character will insure against loss of shear pins and cotter pins and repair tools and is of great convenience on account of its simple and inexpensive construction, the ease with which access may be gained to the tool compartment, and at the same time on account of its protecting the contents of the compartment against water, moisture and resultant corrosion.

The repair tool 19 shown in Fig. 2 is of a special construction and has a portion 20 of reduced thickness for insertion between the ends of the cotter pin to spread the legs of the same. The end of the tool is provided with a portion for engagement with a nut so that the device may be used as a wrench. The opposite end of the tool is provided with a curved portion tapered to a point to be used in removing cotter pins. Since the tool kit or compartment must of necessity be of reduced diameter, the tool 19 is of sufficiently small construction to fit within the same.

If desired a handle such as that shown in Fig. 3 may be employed although the same is less satisfactory. This handle consists of a hand-grip 12 and a single shank 21 of hollow construction and provided with an end closure 22 which provides a sealed compartment. The end of the shank having the plug 22 is adapted to frictionally fit into a socket on the motor. This type of

pull out handle is not as practical as the preferred form of handle shown in the other figures of the drawing.

It will be obvious to those skilled in the art that various changes may be made in my device without departing from the spirit of the invention and therefore I do not limit myself to what is shown in the drawing and described in the specification but only as indicated in the appended claims.

I claim:

1. A detachable steering handle for an outboard motor comprising a pair of hollow telescoped pipe sections, one of said sections having means at one end for attachment to an outboard motor, and the other of said sections being provided with a hand grip, said sections being connected by cooperating externally and internally threaded portions, one of said hollow sections being provided with a reduced hollow extension of an outside diameter to snugly fit within the other section, a removable closure at the end of said extension providing a sealed compartment, said extension forming a reinforcement for the joint between the sections of the handle when the parts are assembled.

2. A detachable steering handle for an outboard motor comprising a pair of telescoped pipe sections, one of said sections having means at one end for attachment to an outboard motor, said sections being connected by screw threads, one of said sections being hollow, the other of said sections being provided with a reduced hollow extension of an outside diameter to snugly fit within the first mentioned section and having a removable closure at the extremity of said extension providing a sealed compartment, said extension forming a reinforcement for the joint between the sections of the handle when the parts are assembled.

3. A steering handle for an outboard motor comprising telescoped pipe sections, one of said sections having means at one end for attachment to an outboard motor and a hollow bore in its opposite end, the other of said sections being provided with a reduced hollow extension of an outside diameter to snugly fit within the bore of the first mentioned section and having a

removable closure at the extremity of said extension providing a sealed compartment, said extension forming a reinforcement for the joint between the sections of the handle when the parts are assembled.

4. A steering handle for an outboard motor comprising telescoped pipe sections, one of said sections having means at one end for attachment to an outboard motor and a hollow bore in its opposite end, the other of said sections being provided with a reduced hollow extension of an outside diameter to snugly fit within the bore of the first mentioned section, said extension forming a reinforcement for the joint between the sections of the handle when the parts are assembled.

5. A detachable steering handle for an outboard motor comprising a pair of hollow sections, means for detachably connecting said sections one to the other, one of said sections being provided with a tubular extension, a removable plug closing the end of said extension, said extension having an external diameter of a size such that when the sections are assembled it will fit snugly within the other section and serve as a reinforcement for the handle.

6. A detachable handle for an outboard motor comprising telescoped sections having coacting means for fastening the same together, one of said sections being provided with an extension projecting into the other section when the parts are engaged, said extension having a closure plug forming a sealed tool compartment therein and said extension also serving to reinforce the handle.

7. In combination with an outboard motor having a handle bracket, a sectional handle connected to said bracket and comprising a hollow section which is pivotal to said bracket and has its outer end threaded, and a handle section which is provided with a hollow compartment providing a tool kit and a grip with an internally-threaded ferrule adjacent thereto, said handle section telescoping into the bracket section with the said threaded end engaging in the ferrule.

TOLBERT FRANK HOBSON.
